UNITED STATES PATENT OFFICE.

HENRY LINCOLN BEACH, OF BROOKLYN, NEW YORK.

CONTAINER.

Application filed March 18, 1926. Serial No. 95,679.

My invention relates to a container adapted to hold various merchandise. I have taken for illustration a box adapted for cigarettes.

5 The invention relates more particularly to a container embodying detachable sections or zones.

The general object of my invention is to provide a container comprising a case and a drawer slideable into and out of the case and to provide detachable sections of a character that the end section after the removal of others will present a closure tab.

Reference is to be had to the accompanying drawings forming a part of this specification, it being understood that the drawings are merely illustrative of one example of the invention.

Figure 1 is a perspective view of a container embodying my invention showing the drawer partially withdrawn from the case;

Figure 2 is a similar view after the removal of portions of the case and drawer;

Figure 3 is a vertical section of the container in closed form;

Figure 4 is a plan view of the blank from which the drawer is formed;

Figure 5 is a plan view of the blank from which the case or body is formed;

30 Figure 6 is a vertical section taken through the container at the bottom as indicated by the line 6—6, Figure 3;

Figure 7 is a fragmentary view in perspective showing the lower portion of the drawer.

In carrying out my invention in accordance with the illustrated example, a body or case 10 is provided and a drawer 11, said case being in the form of a rectangular tube having transverse score lines 12 at the back and front and alining score lines 13 at the ends. Additional longitudinal score lines 14 are provided running from the juncture of a line 12 and a line 13 to the juncture of the next line 12 and line 13.

45 The drawer 11 has side flanges 111 and has score lines 15 across the bottom of the drawer and alining score lines 16, there being longitudinal score lines 116 running from the juncture of one score line 15 at its juncture with the end flange line 16 to the juncture of an adjacent score line 15 with a flange line 16. Thus, the described score lines or other weakened lines divide the case 50 and drawer 11 into detachable sections.

55 In order that the severing of one or more

sections at the weakened lines 15, 16 in the drawer may produce closure tabs, each zone or section has near the side edges oblique lines 18 tapering toward the outer end of the 60 drawer so that the triangular portions outside of said lines 18 may be torn off or otherwise easily removed and the terminal of the drawer will still provide a closure tab 117 which functions substantially like the original closure tab 17. 65

One end of the drawer, that is to say, that end opposite the original closure tab 17 has a closure consisting of an elongated tongue 19 continuous with one side portion of the 70 drawer and a shorter tongue 20 continuous with the other side portion of the drawer, these being folded into the same plane as will be clear from Figure 6 and they are overlaid by a narrow panel 21 having a 75 score line 22 at the base thereof as shown in Figure 4. Integral with the transverse panel 21 forming the end member of the drawer 11 is a terminal flap 23 which is turned over parallel with the bottom of the 80 drawer. Said terminal flap 23 presents a depression 24 having flaring side edges 25 so that the flap conforms substantially to the closure tab 17 or to a tab 117.

A characteristic feature of my improved 85 box equipped with a closure 17 is that when the contents are partially removed, the remaining contents such as cigarettes, for example, may be held tightly to prevent the movement of the contents within the box. 90 This is so because the tab 17 may be tucked far into the case 10, the drawer folding on the transverse score lines 15 and 16 to permit the closure tab 17 to move well into the case.

The score lines 14 and 116 at the angles of 95 the case and drawer permit of the container being knocked down in flattened form for storage or shipment.

It will be readily understood that the sections of the flanges 111 may be removed 100 without removing the sections on the bottom of the drawer between the lines 15 so that the bottom of the drawer may be folded and tucked into the case 10 without removing the sections in certain cases where this would be 105 desirable, without detaching sections of the drawer.

I would state furthermore that while the illustrated example constitutes a practical embodiment of my invention, I do not limit 110 myself strictly to the exact details herein illustrated, since, manifestly, the same can

be considerably varied without departure from the spirit of the invention as defined in the appended claims.

Having thus described my invention, I

5 claim:

1. A container including a case and a drawer slidable into and out of the case, said case and drawer having weakened transverse lines defining detachable sections, said sections of the drawer having oblique lines at the sides to permit end portions of each section to be readily removed and thereby provide a tapered closure tongue upon the removal of one or more

10 sections.

2. A container including a case and a drawer slidable into and out of the case, said case and drawer having weakened transverse lines defining detachable sections, said sections of the drawer having oblique lines at the sides to permit end portions of each section to be readily removed

and thereby provide a tapered closure tongue upon the removal of one or more sections, said case and said drawer having 25 longitudinal weakened lines at the angles for the collapsing of the case and drawer.

3. A container including a case and a drawer slidable into and from the case, said drawer having a terminal closure tab 30 formed with convergent side edges, and a flap at the opposite end of the drawer parallel with the bottom and integral with said bottom, said flap having a depression conforming approximately to the closure tab. 35

4. A container including a case and a drawer slidable into and from the case, said drawer having a closure tab at its outer end and having parallel transverse weakened lines spaced from one another 40 to permit the closure tab to fold well into the case by the collapsing of the drawer along said transverse score lines.

HENRY LINCOLN BEACH.
